US00D931218S

(12) **United States Design Patent** (10) **Patent No.:** **US D931,218 S**
(45) **Date of Patent:** **** Sep. 21, 2021**

(54) **ELECTRICAL DEVICE CONNECTOR**

(71) Applicant: **Physio-Control, Inc.**, Redmond, WA (US)

(72) Inventors: **Christopher Alviar**, Redmond, WA (US); **Neal Clark**, Redmond, WA (US); **Barry Curtin**, Redmond, WA (US); **Neil McIlvane**, Redmond, WA (US); **Peter Nazaroff**, Redmond, WA (US); **Zack Pahlman**, Redmond, WA (US); **Jeremy Wong**, Redmond, WA (US); **Christian Schneider**, Redmond, WA (US)

(73) Assignee: **Physio-Control, Inc.**, Redmond, WA (US)

(**) Term: **15 Years**

(21) Appl. No.: **29/708,058**

(22) Filed: **Oct. 2, 2019**

(51) LOC (13) Cl. **13-03**

CLAIM

The ornamental design for an electrical device connector, as shown and described.

DESCRIPTION

FIG. 1 is a top perspective view of an electrical device connector;

FIG. 2 is a bottom perspective view thereof;

FIG. 3 is a front side view thereof;

FIG. 4 is a bottom view thereof;

FIG. 5 is a back side view thereof; and,

FIG. 6 is a side view.

The Dash-Dash broken lines represent portions of the article that form no part of the claimed design, are directed to environment and represent unclaimed subject matter. The Dot-Dot-Dash broken line represent a boundary of the claimed article and form no part of the claimed design.

1 Claim, 4 Drawing Sheets
